UNITED STATES PATENT OFFICE.

CHARLES HENRY STEPHENS, OF STAMBAUGH, MICHIGAN, ASSIGNOR TO OGLEBAY,
NORTON & COMPANY, OF CLEVELAND, OHIO, A CORPORATION OF OHIO.

METHOD OF SHARPENING DRILLS.

Application filed April 26, 1926. Serial No. 104,552.

This invention relates to methods of sharpening drills and more particularly to methods that are especially adapted for use in sharpening earth drills that are commonly used in mining operations.

It is one of the objects of the invention to provide a comparatively simple and efficient method of sharpening drills that will insure reliable and uniform results and be capable of being performed with comparatively simple and inexpensive equipment.

Other objects of the invention and the features of novelty will be apparent from the following description taken in connection with the accompanying drawings, of which:

Figs. 1 to 6 are side elevations of a drill at different stages in the sharpening operation.

Fig. 7 is a side elevation of a pair of dies used in practicing my improved method, the drill being shown in position therein.

Fig. 8 is a plan of the working face of one of the dies shown in Fig. 7.

Fig. 9 is a rear elevation thereof.

Fig. 10 is a side elevation of the trimming dies with the drill shown in position therein.

Fig. 11 is a plan of the working face of the lower die shown in Fig. 10.

Fig. 12 is a plan of the working face of the upper die shown in Fig. 10, and

Fig. 13 is a side elevation of the drill point after the completion of the sharpening operations.

The stock used in making drills of the class referred to is of the twisted form shown in Fig. 1. In practicing my improved method either for the purpose of sharpening a drill or for forming a new point on a piece of raw stock one end of the twisted rod is flattened, while hot, by any suitable tools such as are commonly used by a blacksmith for that purpose, so as to form the end, to be pointed, substantially as shown in Fig. 2. Thereafter the flattened portion is upset and this operation may be conveniently performed by striking the end of the rod, with considerable force, against an anvil or a heavy metal block, in the manner in which such upsetting operations are commonly performed by a blacksmith. This has the effect of widening the flattened portion as shown in Fig. 3.

The side edges of the flattened end are then symmetrically tapered as shown in

Fig. 4 and provided with spaced gauge-marks which are oppositely arranged in pairs. One corner of the flattened end is then trimmed off from one of the gauge-marks on a line that is inclined with respect to the axis of the drill, the cut being also beveled with respect to the sides of the flattened portion as shown in Fig. 5. The opposite corner is then trimmed off in a similar but reverse manner so as to form the pointed end shown in Fig. 6, with the edges of the point oppositely beveled as required for drilling operations.

It is preferable to perform the various operations, above referred to, on a power hammer in order to expedite the work and in order to be able to use dies which will uniformly sharpen different drills. In Fig. 7 the anvil of a power hammer is indicated at 20 and the movable head or hammer at 21. A die block 22 is secured on the anvil 20, in any suitable manner, and a companion block 23 is secured to the head 21. Each of these blocks has a substantially flat working face 24 a portion of which may be roughened as indicated at 25 and these faces are employed for the purpose of flattening the stock as shown in Fig. 2. One corner of each of the blocks 22 and 23 is cut away as shown at 26 and formed with an inclined working surface 27, these surfaces co-operating to provide the tapered edges of the flattened portion as shown in Fig. 7. The surfaces 27 are provided with transversely extending indentations 28 in the portions thereof which operates on the edges of the drill, these indentations being oppositely arranged in pairs and forming marks or ridges in the tapered edges which serve as gauge-marks in the subsequent trimming operations.

The lower trimming die or shear blade is shown at 29 in Fig. 10, this blade being secured in a holder 30 that is attached to the anvil of the power hammer. The upper shear blade is indicated at 31 and is carried in the holder 32 that is attached to the movable head or hammer, the blades 29 and 31 being diagonally positioned, with reference to the axis of the drill which is shown at 33 in Fig. 10.

The drill is held in an upperly inclined position on the blade 29 with the desired gauge-mark 34 in line with the cutting edges of the blade. By this arrangement a tri-

angular piece is trimmed from one corner of the end of the drill to form one edge of point as shown on 35, Fig. 13. By having the drill arranged in the inclined position as shown in Fig. 10, the edge 35 is beveled with respect to the opposite sides of the drill point. After this trimming operation, the drill is turned 180° to similarly but reversely trim off the opposite corner, thereby forming the edge 36. This completes the sharpening operations. To resharpen a dull drill the operations are identical as for making a drill from raw stock.

In producing different drills in the manner above explained the same gauge-marks will appear thereon, but when drills of different gauges and lengths are produced, different gauge-marks will be utilized in the corner trimming operations.

Having thus described my invention, I claim:

1. The method of sharpening drills which consists in flattening and spreading the end to be sharpened, tapering the flattened portion from the end inwardly toward the shank of the drill, forming a series of gauge-marks on each of the side edges of the tapered portion with the marks of one series

arranged directly opposite the marks of the other series, trimming off one corner of the flattened end on a line from the desired gauge-mark to the intersection of the drill axis with the end of the flattened portion and in a plane that is inclined with respect to the sides of the flattened portion, and then similarly but reversely trimming off the opposite corner of the flattened end and thereby forming a point having oppositely beveled edges.

2. The method of sharpening drills which consists in providing adjacent the end of the drill a flattened portion which tapers inwardly from the end toward the shank and the opposite edges of which have a plurality of oppositely arranged gauge-marks, trimming off one corner of the end portion on a diagonal line from one gauge-mark to the end of the flattened portion, and on a bevel with respect to the sides of said flattened portion, and then similarly but reversely trimming off the opposite corner of the flattened portion and thereby forming a point having oppositely beveled edges.

In testimony whereof, I hereunto affix my signature.

CHARLES HENRY STEPHENS.
